A. G. Burns ATTORNEY.

UNITED STATES PATENT OFFICE.

HARRY LESTER KAST, OF FORT WAYNE, INDIANA.

FOLDING HOOK.

Application filed December 5, 1925. Serial No. 73,339.

This invention relates to improvements in folding hooks for coats, hats and the like, specially for use in automobiles and passenger coaches having low ceilings. The 5 objects of the improvement are to provide a hook of ample proportions upon which wearing apparel may be supported without liability of being shaken from the hook by swaying and irregular movements or jolting 10 of the coach, and which may be folded and pocketed when not in use so as not to interfere with the movements of the occupants.

These objects are accomplished by the construction illustrated in the accompanying 15 drawings, in which:—

Fig. 1 is a side view of the invention;

Fig. 2 is a front view projected from Fig. 1;

Fig. 3 is an end view projected from 20 Fig. 2;

Fig. 4 is a side elevation in section showing the invention in closed position; and

Fig. 5 is a similar view showing the hook 25 extended for use.

The characters appearing in the description refer to parts shown in the drawings and designated thereon by corresponding characters.

The invention consists of a pocket or 30 housing 1, the front of which is open, and which has in its back a pair of screw holes 2 through which screws may be applied in securing the pocket to the frame of a coach or other support. (Not shown.)

35 A hook member consisting of two plates 3 and 4, hinged together, as indicated by 5, is arranged in connection with the pocket. The hinge connection 5 is located at a point spaced from the outer end of the plate 3 so that the lower end of the plate 4 upon coming into contact with the adjacent inner face of the plate 3 limits the swing of the plate 4 when it reaches an obtuse angle relative to the plate 3.

45 The plate 3 has fixed thereon at a point spaced from its end opposite the hinge 5 an elongated loop 6 through which a stationary pin 7 fixed in the lower part of the housing extends and thus secures the hook member 50 in connection with the pocket. The pin 7 is located adjacent the front and bottom of the

pocket, and a second stationary pin 8 extends in the housing adjacent the back and bottom thereof, there being space between said pins and the bottom wall 9 of the 55 pocket to receive the end of the plate 3 when the latter is moved into horizontal position. The plate 3 has also adjacent its hinged end, upon the outer face, a knob 10 by means of which the hook member is manipulated, and 60 the pocket has a pendant hook 11 for the suspension of small articles thereon independent of the folding hook member.

In utilizing the invention the pocket is secured permanently in position upon the 65 frame work of a coach at a suitable elevation, preferably adjacent the ceiling thereof, between windows. When desired for use, the hook member is swung into extended 70 position by manipulating the knob and unfolding the plate 4. The plate 3 is moved backwardly after reaching horizontal position so that its inner end projects beneath the pin 8, which pin serves as a fulcrum for the plate 3 to sustain it in its extended position. The hook member thus positioned may be utilized by depositing thereon garments, or other articles of apparel, umbrellas, etc. The folding plate being of suitable length affords ample capacity for the reception of 75 the articles, and the erect plate forming the outer section of the hook member affords especially a secure support for such an article as a hat, which because of the length of the plate, is unlikely to be accidentally 80 dislodged therefrom. When use of the hook member is not required, the plate 3 is drawn forward out of engagement with the pin 8 and the plates are then folded together and 85 swung upon the pin 7 upwardly into the 90 front of the pocket out of the way of the occupants of the coach, the folded hook member serving also to close the pocket.

What I claim is:—

1. In a device of the class described, a 95 housing attachable to the frame of a coach, and having an open front, a pair of transversely disposed pins within said housing and adjacent the lower end thereof, and a folding hook member composed of sections 100 hinged together so as to have limited pivotal action, one of said sections having an elong-

gated loop through which one of said pins extends, and having fulcrum bearing with the other of said pins and supported relation with the bottom of said housing when said hook member is extended for use, said member being operable to fold and close the front of the housing.

2. In a garment hanger a housing support and a folding hook member composed of sections hinged together one of which has

support on one end in said housing and limited sliding movement therein, and a fulcrum in said housing for said one section, the other section having hinged connection with the opposite end of the former section so that its outward swinging movement is thereby limited. ¹⁵

In testimony whereof I affix my signature.

HARRY LESTER KAST.
